UNITED STATES PATENT OFFICE.

CHARLES FRANCIS POLACK, OF YORK, PENNSYLVANIA.

WINDOW FASTENER.

Application filed April 30, 1927. Serial No. 187,905.

This invention relates to window fasteners of an automatic type, that is to say, which will automatically latch when the two sashes are moved into a window closed position.

The invention consists in providing a casing member containing a spring pressed latch element which has a handle portion projecting therefrom, said casing being adapted to be secured to one window sash, and a complementary shell having a projection or detent for automatic engagement with the latch when the two window sashes are brought together.

The invention further consists in the novel arrangement, combination and construction of parts shown and described.

In the drawings:

Fig. 1 is a perspective view showing one embodiment of my invention.

Fig. 2 is a top plan view.

Fig. 3 is a bottom view.

Fig. 4 is a sectional elevation along the line 4—4 of Fig. 2.

Fig. 5 is a side view of one of the casing elements.

Fig. 6 is a detail of the latch.

In the embodiment illustrated, I have shown a window sash at 1 to which is secured a casing 2 having preferably a turtle back portion 3 and a window 4.

A latch element comprising the latch proper 5 and a handle 6 angularly disposed thereto, is pivoted to the casing 2 as by pin 7. A projecting stud 8 on the latch 5 is encircled by a spring 9, one end 9^a of the spring engaging the latch 5, the other end 9^b of the spring engaging the casing wall. In the form shown, the latch proper 5 is provided with a boss 11 upstanding from the end thereof, of substantially triangular form, adjacent to and formed by a cut away section 12. The under edge 13 of the latch 5 is rounded off for a purpose specified hereinafter.

It will be observed that the turtle back portion of the housing covers the spring and pivot portion of the mechanism, thus protecting the same from dirt and preventing access to these parts when the sashes are together. The handle 6, projects through the window or open part of the casing element so as to be readily grasped and manipulated in unlatching and opening the casement or window.

The other or complementary shell 14 is shaped similarly to the casing 2 except that no window is provided. Cut into the top edge facing its complementary shell 2 is a

recess 15 having one of its edges beveled as at 16 to be slidingly engaged by the latch edge 13. Beneath the beveled portion 16 I provide a lug 17 of substantially triangular form projecting downwardly from the under face of the shell to adjacent its edge. One side of this lug 17 forms in effect an extension of one of the side walls of the recess 15. When the parts are latched, the boss 11 on the latch end 5 is adapted to be behind the lug 17 and this lug occupies a position in the cut away section 12 as shown in Figs. 3 and 4.

It is to be noted that the boss and stud are similarly shaped but reversely placed and that when the parts are in latched position their meeting faces make an angle with the meeting edges of the complementary shells. This has a distinct advantage in that should the window sashes become warped, and the shells become thereby slightly askew, the latch and boss may still engage each other thus allowing considerable latitude during the window life.

In practice, each shell is to be secured to one of the meeting rails of a window sash, so that when the sashes are in the window closed position, the two shells will lie together, the boss 11 behind the lug 17, and this lug in the cut away section 12.

To unlatch the window, the handle 6 is pressed toward the window pane, which draws the latch within the periphery of the turtle back portion of the shell or casing 2. This releases the other shell and therefore the other sash and permits the window to be opened.

When the two sashes are moved to window closed position, the casing 2 will approach shell 14 from above, and the latch end 5 will strike the beveled face 16 of the shell 14 and slide over the same while the sash is being moved downwardly, and against the tension of the spring 9, until the latch end 5 clears the lug 17. At this point the boss 11 will snap behind the lug and the window will be secure.

It will be observed that by the use of these instrumentalities, a latch is provided of simple construction, which will automatically lock and which may be readily and quickly released, which has all its moving parts enclosed and which is extremely simple and cheap to construct.

What is claimed is:

A window latch comprising a casing attached to one window sash, a pivoted spring

pressed latch therein, a complementary shell adapted to be attached to the other window sash, a triangular stud projecting downwardly from beneath the shell and a similar shaped but reversely placed boss on the latch engageable with said stud, the meeting faces of the boss and stud making an angle with the meeting edges of the complementary shells the latch being normally pressed outwardly by

its spring beyond the periphery of the first mentioned shell, said last mentioned shell having a cutaway portion to clear the projecting end of the latch, said shell having a portion of its surface adjacent the cut-away portion beveled to facilitate the passage of the latch end through the cut-away portion.

In testimony whereof, I affix my signature.
CHARLES FRANCIS POLACK.
